ATTORNEYS

UNITED STATES PATENT OFFICE.

HENRY K. HESS, OF SYRACUSE, NEW YORK.

BUILDING UNIT.

1,291,879.

Specification of Letters Patent.

Patented Jan. 21, 1919.

Application filed March 23, 1918. Serial No. 224,190.

To all whom it may concern:

Be it known that I, HENRY K. HESS, a citizen of the United States, and residing at Syracuse, in the county of Onondaga and 5 State of New York, have invented a certain new and useful Building Unit, of which the following is a specification.

This invention has for its object a building unit particularly applicable for decorative purposes where marble or other decorative 10 stone work has been heretofore used and where durability and sanitation as well as ornamentation are factors, as in bars, soda water fountains, furniture and parts thereof, wainscoting, baseboards, panels, window sills, columns and building blocks, etc., which building unit is simple and economical in construction and capable of wide variations 15 in ornamental effect and especially simulates the crystalline effect of natural stones as the various marbles.

In describing this invention, reference is had to the accompanying drawings in which like characters designate corresponding 20 parts in all the views.

Figures 1 and 2 are face and rear elevations of one form of this building unit, the glass plate being broken away in Fig. 1 to expose the underlying decorative sheet and 25 the backing and sheet being broken away in Fig. 2 to expose the rear face of the glass plate.

Fig. 3 is a transverse sectional view of this building unit, the same being shown as 30 provided with a wood back or body.

Fig. 4 is a fragmentary sectional view of another form of my building unit showing the same as provided with a cement body or back.

Fig. 5 is a sectional view of a block as a window sill having two of its sides faced with my invention.

Fig. 6 is a fragmentary elevation of the window sill shown in Fig. 5.

Fig. 7 is a face view of my building unit having a different form of marginal holding wire from that shown in Fig. 2.

Fig. 8 is a sectional view showing the marginal wire as projecting through the rear 50 instead of the edge face of the glass plate.

This building unit comprises a plate or layer of glass 1 having indentations in the rear face thereof providing prismatic projections 2 having light reflecting and deflecting faces 3 arranged in planes at inclined

angles to the plane of the front face of the glass, the projections being arranged at various angles to each other, and a decorative sheet 4 on the rear face and spaced apart from said faces, the sheet engaging the 60 apexes of the projections. It also preferably includes a body or back 5, and means for securing the plate 1 to the body or back, the sheet 4 being interposed between the body or back and the plate. 65

The projections 2 are here shown as arranged in groups, the projections 3 of each group radiating along from a common center 6 in order that some of said faces 3 will always be in position to reflect and deflect 70 light to the eye of the observer irrespective of where he is standing and the direction from which the light is cast upon the glass plate 1. Hence, the crystalline effect of 75 natural stone is produced in any position of the observer.

Usually, the groups are connected by additional reflecting and deflecting faces 7 formed by straight corrugations in the rear side of the plate 1 between the groups. 80

The reflecting and deflecting faces 3 and 7 prevent the design on the sheet 4 from showing too boldly through the glass by spreading and merging the lines thereof.

The sheet 4 may be of paper, cloth or wood 85 or other material on which the design is sketched, painted or printed, or the surface of which is colored or tinted. Hence, the decorative sheet can be manufactured in quantities at a low cost. When the sheet 4 90 is assembled with the plate 1 with its reflecting and deflecting faces, the whole presents the appearance of highly polished high grade marble or artificial stone having crystals therein. 95

The glass plate may be formed with marginal loops 8 of wire having portions embedded in the margin and other portions 8^a extending outside of the plate where they can be secured to a suitable support or to the 100 backing.

As seen in Fig. 4 the loops 9 extend through the edge face of the glass and may be bent in position so that they are embedded in the back or body of cement cast onto the rear face of the glass and the interposed decorative sheet or secured to a wood back. The margin of the glass in which the loops are embedded may be provided with an opaque border 10 to conceal the portions of 110

the loops embedded in the glass. In Fig. 8 the loops 11 extend through the rear face of the glass.

In Figs. 5 and 6 a unit is shown in which 5 the glass facing is provided on two sides thereof to be used in situations where two faces are exposed as in window sills.

In Figs. 7, the marginal wire 12 is shown 10 as looped in spiral form so that the plate will hold together if it should crack entirely across. In the form shown in Fig. 3, if a crack extended into the open side of loops 15 at opposite margins of the glass the sections of the glass would fall apart, while in the form shown in Fig. 7 the sections are bound together within the body of the glass by the wire loops.

This building block is particularly advantageous in that the crystals of natural 20 stone can be simulated in a simple and economical manner and further in that the unit can be produced in any size and cut up into smaller sizes, and manufactured at a low cost compared with the natural stone 25 or imitations thereof and the design is readily changed and any natural stone effect can be readily produced.

What I claim is:

1. A building unit comprising a layer of 30 glass having groups of indentations on the rear side thereof providing prismatic projections having angular light reflecting and deflecting surfaces, the indentations of each group radiating along their lengthwise 35 dimension from a center and said faces along their widthwise dimension being arranged in planes at oblique angles to the plane of the front face of the glass, and a decorative sheet on the rear side of the glass layer

and spaced apart from said faces, substantially as and for the purpose described. 40

2. A building unit comprising a layer of glass having indentations on the rear side thereof, providing prismatic projections having angular light reflecting and deflecting 45 surfaces arranged in planes at inclined angles to the plane of the front face of the glass layer, a back or body, and a decorative sheet interposed between the body and the glass layer, and spaced apart from said faces, substantially as and for the purpose 50 specified.

3. A building unit comprising a layer of glass having indentations on the rear side thereof providing prismatic projections having angular light reflecting and deflecting 55 surfaces arranged in planes at inclined angles to the plane of the front face of the glass layer, a back or body, and means for securing the glass to the body, substantially 60 as and for the purpose set forth.

4. A building unit comprising a layer of glass having indentations on the rear side thereof providing prismatic projections having angular light reflecting and deflecting 65 surfaces arranged in planes at inclined angles to the plane of the front face of the glass layer, a back or body, a decorative sheet interposed between the body and the glass layer and spaced apart from said faces, 70 and means for securing the glass to the body, substantially as and for the purpose described.

In testimony whereof, I have hereunto signed my name, at Syracuse in the county 75 of Onondaga, and State of New York, this 7th day of March, 1918.

HENRY K. HESS.
